UNITED STATES PATENT OFFICE

142,000

DESIGN FOR A FOUNTAIN PEN

Maurice J. Waldinger, Flushing, N. Y.

Application November 25, 1944, Serial No. 116,559

Term of patent 14 years

(Cl. D74—17)

To all whom it may concern:

Be it known that I, Maurice J. Waldinger, a citizen of the United States of America, residing at Flushing, Long Island, in the county of Queens and State of New York, have invented a new, original, and ornamental Design for a Fountain Pen, of which the following is a specification, reference being had to the accompanying drawing, forming part thereof.

tain pen showing my new design thereof, with the writing point covered by the cap.

Figure 2 is the back elevational view of the fountain pen with the cap removed.

I claim:

The ornamental design for a fountain pen, substantially as shown.

MAURICE J. WALDINGER.
